UNITED STATES PATENT OFFICE.

JEAN ADAM GEORG IFFERT, OF FRANKFORT-ON-THE-MAIN, GERMANY, ASSIGNOR TO
UNITED SHOE MACHINERY COMPANY, OF PATERSON, NEW JERSEY, A CORPORA-
TION OF NEW JERSEY.

PULLING-OVER MACHINE.

1,147,172.

Specification of Letters Patent. Patented July 20, 1915.

Application filed August 17, 1912. Serial No. 715,635.

To all whom it may concern:

Be it known that I, JEAN ADAM GEORG IFFERT, of Frankfort-on-the-Main, Germany, a subject of the King of Prussia, 5 have invented certain Improvements in Pulling-Over Machines, of which the following description, in connection with the accompanying drawings, is a specification, like reference characters on the drawings 10 indicating like parts in the several figures.

This invention relates to pulling over machines and is herein shown as embodied in a machine of the type shown in United States Letters Patent No. 663,777, granted December 11, 1900, on application of R. F. Mc- 15 Feely. In the use of machines of this type there are numerous occasions for taking a shoe out of the machine without fastening it as, for example, because the operator gets 20 the shoe in the machine incorrectly or some peculiarity of the work develops after the upper has been strained which requires attention before completing the operation. Each gripper must be released before the 25 shoe can be taken out and to do this the operator reaches into the machine with a screw driver or other tool and engages the tripping devices, the commercial grippers being made with tripping devices substan- 30 tially like those shown in United States Letters Patent 1,030,264, granted June 18, 1912. By this procedure the grippers which are holding the upper under tension are freed one at a time and when the first side 35 gripper is released the other one draws the upper transversely about the last, pulling it out of shape and sometimes permanently injuring it.

The object of this invention is to provide 40 conveniently operating means by which a plurality of grippers of this machine including both the side grippers, can be released easily and simultaneously without the use of extraneous tools and without liability of 45 injuring the shoe.

The several features of the invention will 50 be more fully understood from the following description in connection with the accompanying drawings and will then be pointed out in the claims.

Figure 1 is a side elevation of so much of the pulling over machine as is necessary to illustrate to enable this invention to be understood. Fig. 2 is a front elevation.

The machine comprises two grippers engaging the upper at each side of the shoe and supported from levers 2, 2, and one gripper engaging the upper at the end of the toe and suspended from a lever 3. The levers 2 and 3 extend back to a fulcrum and 50 from thence to a yielding connection with cams operated by power. Through the yielding connections the levers raise the operating bars 168 of the grippers which, as described in the later of said patents, first effect closure 65 of the gripping jaws and then lift the grippers to pull the upper at the end and sides of the last, after which the machine comes to rest and then, after such adjustments of the upper as may be required and can be 70 made with the shoe in the machine, the machine is restarted and caused to overdraw and to fasten the upper, the grippers being released by the incoming of the tackers which strike and operate the trippers 75 204.

To the machine as so constructed there is added in accordance with this invention a gripper releasing mechanism. Upon pivot studs 10 projecting from the machine frame is fulcrumed a lever attachment 12 in the 80 form of a yoke, the cross bar of which carries two arms 14, 15 that extend forwardly and have rolls 16 on their front ends. The arm 15 carries two rollers which are arranged to engage respectively the one side 85 gripper lever 2 and the toe gripper lever 3 while the roller on the arm 14 engages the other side gripper lever 2 as shown in Fig. 2. To the lever attachment 12 at one end is securely fastened the operating arm 20 which 90 projects forwardly and upwardly into convenient position to be engaged by the right hand of the machine operator. A friction clasp 22 of the knife switch type may hold the lever attachment normally in an up- 95 raised position at or above the upper limit of the levers 2, 2, 3. If a shoe is found when the machine stops with the upper under tension to be in such condition as to require that it be taken out of the machine without 100 fastening, the operator can pull down the lever 20 with his right hand while having his left hand free to catch the shoe when it is released. The downward actuation of the lever attachment lowers the grippers, the 105 yielding connection of levers 2, 2, 3 with their power operating cams permitting this, toward and substantially to their starting

position thus first relaxing the tension on all the grippers at once and then opening the jaws to release them from the shoe.

Having explained the nature of this invention and described a preferred construction embodying the same, I claim as new and desire to secure by Letters Patent of the United States:—

1. In a pulling over machine having a plurality of grippers arranged to engage an upper at opposite sides of a last and power operating mechanism to cause the grippers to seize the upper, pull it, and then come to rest holding the upper under tension for examination; updraw levers extending from front to back of the machine and fulcrumed between their ends, and means arranged above the shoe to be engaged and operated by one hand of the workman while the other is free to receive the shoe and having operative connections with both said updraw levers between their fulcrum and the side grippers to disconnect them simultaneously from the shoe.
2. In a pulling over machine the combina-

tion with the yieldingly actuated updraw levers 2, 2, 3, and the side and toe grippers connected therewith, of a lever attachment pivotally mounted above the levers 2, 2, 3 and having arms to engage said levers and an operating bar 20 by which to depress all the updraw levers together.

3. In a pulling over machine the combination with the yieldingly actuated updraw levers and the side grippers connected therewith, of a lever having separate arms extending over the updraw levers, means for retaining the lever normally upraised, and a hand bar by which said separate arms may be caused to depress the updraw levers and release the side grippers from the upper simultaneously.

In testimony whereof I have signed my name to this specification in the presence of two subscribing witnesses.

JEAN ADAM GEORG IFFERT.
